UNITED STATES PATENT OFFICE.

MARTIN P. COLE, OF GOODLAND, KANSAS.

TIRE BOOT.

Application filed September 20, 1927. Serial No. 220,753.

This invention relates to a patch or a boot for the outer casings of pneumatic tires, and is designed primarily for use in connection with balloon and high pressure tires, but it is to be understood that a patch or boot in accordance with this invention may be employed for any purpose for which it is found applicable, and the invention has for its object to provide, in a manner as hereinabove set forth, a non-slip, strong, durable, inexpensive, flexible, expeditiously applied, self-vulcanizing patch or boot for a split, blow-out or crack in a tire casing to close it in a thoroughly efficient manner.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a patch or boot, in accordance with this invention, of the rectangular or oblong type.

Figure 2 is a section on line 2—2 Figure 1.

Figure 3 is a top plan view of a modified form of patch or boot, in accordance with this invention, and for use in connection with the side wall of the casing of a tire.

Figure 4 is a section on line 4—4 Figure 3.

Figure 5 is a top plan view of another modified form of a patch or boot and of the circular type.

Figure 6 is a section on line 6—6 Figure 5.

Figure 7 is a fragmentary view in cross section of the outer casing of a tire showing the adaptation therewith of a patch or boot in accordance with this invention.

Each of the forms of patches or boots shown is of like construction, with this exception that the contour of each in plan is different and as shown in Figures 1 and 2, the patch or boot is oblong, in Figures 3 and 4 semi-oval, and in Figures 5 and 6 circular. The patch or boot in cross section is set up to conform to the shape of the tire.

Each patch or boot shown comprises a body portion formed of a plurality of rubberized cord fabrics taken from an old tire

casing, which has been vulcanized, and the stretch taken out. As illustrated, by way of example, in connection with each patch or boot, the body portion is formed of two plies of rubberized cord fabric.

Each patch or boot further comprises a flexible base cut from a discarded inner tube and which prevents the chafing or pinching of the inner tube of a tire when the patch or boot is secured in position. The body portion of the patch or boot is secured upon the outer face of the base, is of less size than the size of the latter and has its edge or edges spaced inwardly of the edge or edges of the base.

Each patch or boot further comprises a flexible covering for the body portion and which consists of a plurality of stepped plies, depending upon the strength desired, which are cut or taken from a discarded inner tube. The inner ply of the covering completely encloses the body portion of the patch.

The base, plies of the body portion and plies of the covering are buffed and treated with a suitable rubber solution and are vulcanized together solidly, and will not slip or move in the tire.

The contour of the plies of the body portion and the contour of the plies of the covering for the body portion conform in shape to that of the base of the patch or shoe.

Referring to Figures 1 and 2 of the drawings 1 indicates a base, which is of oblong contour, 2, 3 the plies of the body portion, 4, 5, 6 the plies of the covering for the body portion and 7 cushion gum covering all layers on the stepped down face of a patch or boot for the purpose of insuring adhesion and self-vulcanization when the patch or boot is mounted in position.

Referring to Figures 3 and 4 of the drawings 1' indicates the base which is of semi-oval contour, 2', 3' the plies of the body portion, 4', 5' plies of the covering and 6' the cushion gum or adhesive material.

Referring to Figures 5 and 6 the base of the patch or boot is of circular contour and indicated at 1'', the plies of the body portion at 2'', 3'', and the plies of the covering at 4'', 5'' and 6''. The cushion cement or gum is indicated at 7''.

In Figure 7 of the drawings a tire is illustrated at 8, and which is provided with a crack 9 and secured to the inner face of the tire or outer casing 8 is a patch or boot 10 for closing the crack 9.

The patch or boot is self vulcanizing and made to fit all sizes of balloon and high pressure tires. When the patch or boot is mounted in position it will not chafe the 5 casing or inner tube or pinch the latter. The form of patch shown in Figure 3 is to be employed with a side wall of the outer casing of the tire. The patch or tire can be constructed so that it can be used with 10 a hole or cavity of any size and whereby the life of the outer casing will be materially increased.

It is thought the many advantages of a patch or boot, for use in connection with 15 the outer casings of pneumatic tires, as constructed in accordance with this invention can be readily understood, and although the preferred embodiment of the invention is as illustrated and described, yet it is to be understood that changes in the details 20 of construction can be had which will fall within the scope of the invention as claimed.

What I claim is:—

1. A self-vulcanizing patch or boot for 25 the outer casings of pneumatic tires comprising a composite body portion having the elements thereof vulcanized together and consisting of a flexible base, a body portion formed of a plurality of plies of non- 30 stretched material and of a material differ-

ent from that of the base, a flexible covering formed of a plurality of plies of material and of a material different from that of said body portion, and said covering and body portion arranged in stepped relation, and a coating extending completely throughout the outer face of said covering and possessing a characteristic to provide for the self-vulcanizing of said body to the inner face of the outer casing of a tire. 35

2. A self-vulcanizing patch or boot for the outer casings of pneumatic tires comprising a composite body having the elements thereof vulcanized together and consisting of a flexible 40 base taken from an inner tube, a body portion formed of a plurality of plies of non-stretched material and taken from the outer casing of a tire, and a flexible covering formed of a plurality of plies taken from an inner tube, said covering and body 45 portion arranged in stepped relation, and a coating extending entirely throughout the outer face of said covering and possessing a characteristic to provide for the self-vulcanizing of said body with the inner face 50 of the outer casing of a tire. 55

In testimony whereof, I affix my signature hereto.

MARTIN P. COLE.
